(57) **CLAIM**

The ornamental design for a wrist rest for plucked string instruments, as shown and described.

DESCRIPTION

The patent or application file contains at least one drawing executed in color. Copies of this patent or patent application publication with color drawing(s) will be provided by the Office upon request and payment of the necessary fee.

1. Wrist rest for plucked string instruments

1.1 : Front

1.2 : Top

1.3 : Bottom

The characteristic features of the ornamental design are the shape of the wrist rest for plucked string instruments (e.g. guitar), as shown.
